UNITED STATES PATENT OFFICE.

WILLIAM H. ROBBINS, OF SPRINGFIELD, OHIO, ASSIGNOR TO THE WILLIAMS COMPANY, OF LONDON, OHIO, A CORPORATION OF OHIO.

STEEL-WOOL-REMOVING MACHINE.

Original application filed June 5, 1925, Serial No. 35,155. Divided and this application filed February 18, 1926. Serial No. 39,244.

My invention relates to steel wool machines and in particular to means for conveying away the strands of steel wool therefrom; and is a division of my application 5 Serial No. 35,155 filed June 5, 1925.

It is the object of my invention to provide means for engaging the delicate steel wool strands and for moving them at a predetermined desired speed away from the steel 10 wool machine as they are manufactured in such a way as to move them positively without injuring the strands.

It is a further object of my invention to provide means of engaging with the strands 15 so as not to break them but to still frictionally engage them in such a way that the pull on the strands to remove them away from the machine will be uniform, constant and steady so that the strands will not be 20 broken.

Referring to the drawings:

Figure 1 is a side elevation of one form 25 of the steel wool removing apparatus of my invention located adjacent to a diagrammatic illustration of a typical steel wool machine;

Figure 2 is a plan view of one end of the removing means shown in Figure 1;

Figure 3 is a section on the line 3—3 of 30 Figure 1 showing the supporting bracket broken away and the supporting shafts in section with a strand of steel wool passing between the steel wool actuating members;

Figure 4 is a similar view on the line 4—4 35 of Figure 5 showing a modified form of the steel wool removing means;

Figure 5 is a plan view of a modified form 40 of this removing means consisting of spaced rods;

Figure 6 is an end elevation of another form of steel wool removing means using solid rolls which frictionally engage with the steel wool strands passing between them;

Figure 7 is a plan view of this modified 45 form illustrated.

Referring to the drawings in detail, 1—1 are standards for supporting the steel wool machine table 2 on either end of which is mounted the supporting brackets consisting 50 of the upright members 3 which terminate in spaced members 4, thus forming Y-shaped brackets at either end of the machine. It will be understood that this steel wool removing means may be located anywhere,

that is, above, below or at one side of the 55 steel wool machine but for the purpose of illustration and the ease thereof, I have shown it in a typical satisfactory form above the machine. Journalled in the ends of these arms 4 of the Y-shaped bracket are the 60 shafts 5 and 6 which are thus supported in parallel relationship. On one of these shafts is mounted a pulley 7 actuated by a belt 8 from any suitable source of power. These shafts have mounted thereon, opposite to one another, the gears 9 and 10 which 65 mesh with one another and serve to turn the shafts 5 and 6 in unison with one another so that there will be synchronous movement of the shafts and any means which they may 70 carry. The shafts carry, on suitable end supporting members or plates 11 corrugated drums 12, such corrugations being formed as round topped ridges 13 which are relatively widely spaced with deep valleys 14 75 therebetween. These two corrugated drums have their projecting corrugations or ridges 13 adapted to project within the corresponding valleys 14 on the other corrugated drum but the drums are so positioned through the 80 gearing 9 and 10 that while successive ridges project into opposite successive valleys, yet the drums do not touch each other but are spaced a sufficient distance between their adjacent surfaces to accommodate the steel 85 wool strands 15 passing from the steel wool cutting tools 16. These strands are fed between the corrugated rolls and are bent in serpentine form as they pass between the 90 corrugations of the rolls where the corrugations of the rolls are adjacent, thus providing a frictional engagement for moving the strands. The strands are therefore moved by this engagement at a predetermined speed without jerking or pulling and without rupture of the strands but they are nevertheless positively moved. The strands are easily examined as they are thus moved from the machine enabling the operator to 95 make the adjustments on the cutting tools as may be desired.

These strands are cut from the wire 17 passed over the drums 18 in the usual manner. These drums are mounted on the table 2 on the vertical spindles 19. It will be 100 understood, however, that the details of the steel wool machine are immaterial as one or more wires may be used and other de-

tails of the machine may be modified. The drums shown in Figures 1, 2 and 3 are preferably formed of corrugated sheet metal. In Figure 4 an open type of removing mechanism is illustrated where it is desired to have this form which provides for a circulation of air. The mechanism is the same with the exception that instead of having actuating drums with continuous faces, rods 10 are provided mounted on the crests of the teeth 21 of the end members 22. The wall engages with the rods which loosely interlock as in the case of the forms shown in Figures 1, 2 and 3, not touching each 15 other and being sufficiently spaced to accommodate the steel wool strand which is frictionally engaged by the rods and moved away from the tools.

Referring to the form shown in Figures 20 6 and 7, it will be observed that the mechanism is the same save that two solid, smooth-faced rolls 23 are employed which are sufficiently spaced to a minute degree not to engage one another but to insure 25 frictional engagement with the fine strands of wool which pass therebetween.

It will be understood that I desire to comprehend within my invention such modifications as may be necessary to adapt it to 30 varying conditions.

Having thus fully described my invention, what I claim as new and desire to secure by Letters Patent, is:—

1. In a steel wool machine a plurality of 35 cutters, feeding means for feeding a wire to said cutters, means to remove steel wool strands from the cutters individually consisting of a pair of synchronously moving, closely adjacent steel wool engaging mem-

bers spaced apart from each other whereby 40 a circulation of air is permitted and adapted to frictionally engage the wool strands to pull them away from the machine, said members being adapted to move together synchronously but not to engage one another 45 and only adapted to frictionally engage with the steel wool strands passing therebetween without tension, and said members being furthermore so arranged that their alternate projections and depressions on said 50 members, the projections of one member adapted to project into the depression of the other member without engaging with the member and the strands being adapted to pass between the alternate projections and 55 depressions in the members where they are adjacent to one another, thus frictional bends being formed in the steel wool strands to assist in pulling the strands away 60 from the machine.

2. In a steel wool machine a plurality of cutters, feeding means for feeding a wire to said cutters, means for removing steel wool strands from said cutters individually consisting of a pair of parallel spaced shafts, 65 means for causing said shafts to rotate together, means on said shafts to carry a plurality of spaced rods whereby a circulation of air is permitted and adapted to project one of the rods on one shaft between two 70 rods on the other shaft as they come opposite to one another without said rods touching, the space being sufficient to pass a steel wool strand therebetween for frictional engagement with the rods.

In testimony whereof, I affix my signature.

WILLIAM H. ROBBINS.
